United States Patent Office.

P. DUNHAM, OF LEEDS, MASSACHUSETTS.

Letters Patent No. 92,944, dated July 27, 1869.

IMPROVEMENT IN STOP-MOTIONS FOR SILK-STRETCHING AND WINDING MACHINES.

The Schedule referred to in these Letters Patent and making part of the same.

To all whom it may concern:

Be it known that I, P. DUNHAM, of Leeds, Hampshire county, Commonwealth of Massachusetts, have invented a new and useful Machine for Stretching Silk; and I do hereby declare that the following is a full and clear description thereof, reference being had to the accompanying drawings, and to the letters of reference marked thereon.

In the drawings—

Figure 1 is a side sectional view, and

Figure 2 is a front view of my device.

This invention consists of a new and improved device for stopping the motion of the stretching-pulleys, in machines for stretching silk, before it is wound upon the bobbin finally.

In the drawings—

A is the reel, from which the silk is wound to the bobbin C above it.

Between the reel and bobbin are pulleys B and B', geared together, by means of the gears a and a', on their shafts, and the intermediate gear-wheel b on the shaft of the operating-pulley D, which takes its motion from the main shaft E of the machine, by means of a belt, F.

The gears a and a' are of the same size, and both being turned by the gear b, consequently move the pulleys B and B' at the same rate of speed.

It will be seen, however, that the pulleys B and B' are differential ones, each having small grooves d and f, the ones, d, being cut into the part of less diameter, and the ones, f, into parts of greater diameter.

Now, the thread, in passing from the reel to the bobbin, is passed intermediately around the pulleys B and B', in the following manner: first, from the reel around the groove d of the pulley B', then around the corresponding part of the pulley B, then back again around the part f of the pulley B', and finally, around

the same part of the pulley B, so that it has to stretch in order to accommodate itself to the different sizes of the parts, the pulleys moving, as before stated, at the same speed.

Should the thread break, from any accidental cause, in this operation, the machine is stopped by means of the following device:

A lever, I, is pivoted, at g', to the frame of the machine, so that the longer arm, h, rests upon the thread at a point between the two cross-bars j and j', over which the thread passes before it reaches the bobbin. When the thread breaks, this arm falls from its position, and brings the shorter arm, k, with a hook on its end, in the way of a catch on the pulley B, which clutches and stops the motion.

This catch l of the pulley B is made with a spring, so that the machine is not stopped too suddenly.

The silk is generally kept wet upon the reel, so that it stretches better.

In this manner the silk is stretched evenly and fully without danger of breaking, except in the case of flaws in the fibre, and, in such a case, the machine is instantaneously stopped, without danger of breaking any of the operative parts by the sudden jarring which usually accompanies the ordinary stop-motions.

Now, having described my invention,

What I claim as new, and desire to secure by Letters Patent, is—

The arrangement of the lever I, with hook-arm k, upon the frame, and the spring-catch l upon the pulley B or its shaft, all substantially as described, and so that the breaking of the thread causes them to engage and stop the machine, as set forth.

P. DUNHAM.
